CLAIM

We claim the ornamental design for a washing machine, as shown and described.

DESCRIPTION

FIG. 1 is a front perspective view of a washing machine showing our new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof; and,

FIG. 8 is an enlarged front perspective view of the claimed portion of the washing machine.

The broken lines in the figures depict environmental subject matter and form no part of the claimed design.

1 Claim, 8 Drawing Sheets
